UNITED STATES PATENT OFFICE.

ALFRED G. HOLCOMBE, OF NEW YORK, N. Y., ASSIGNOR TO THE EQUITABLE ELECTRIC COMPANY, OF SAME PLACE.

AUTOMATIC RESPONDING-INSTRUMENT FOR ELECTRIC CIRCUITS.

SPECIFICATION forming part of Letters Patent No. 319,718, dated June 9, 1885.

Application filed August 7, 1884. (No model.) Patented in England August 27, 1884, No. 11,715.

To all whom it may concern:

Be it known that I, ALFRED G. HOLCOMBE, a citizen of the United States, residing at New York, county and State of New York, have 5 invented a certain new and Improved Automatic Responding-Instrument for Electric Circuits, (for which a patent was obtained in Great Britain, No. 11,715, bearing date August 27, 1884,) of which the following is a specification.

10 This invention consists of certain improvements in the art of electrical communication, whereby a person calling up a distant station or subscriber is automatically notified whether any one is there present to receive his message, or to be put in communication with another station or subscriber, or is notified of the time when said called station will be attended or ready to receive messages if the attendant be absent, thus saving considerable 15 time to the operator making the call, as he will refrain from continually renewing the call, as he now does, if it is not immediately responded to, and will wait until the time indicated before he again calls up said station or 20 subscriber.

In this application I have described and claimed the means for carrying out my invention; and a division of this application embraces a description of the principle and a 25 claim covering the method of operation. To accomplish this desirable result, I arrange in close proximity to the call apparatus or bell an automatic responding-instrument operated by means of a spring or other motor and locked 30 or prevented from acting by the armature or other moving part of the call apparatus or bell when the same is inoperative or in its normal position. The call apparatus and responding-instrument may be contained in one 35 case. This automatic responding-instrument is constructed to pass to line currents induced from the action of an independent battery in certain predetermined impulses upon the call apparatus or bell being actuated from the calling-station, which actuation of this calling apparatus or bell releases the responding-instrument, which is immediately operated by the motor, and so sends the predetermined signal to the calling-station. These automatic responding-signals may be of any arbitrary char- 40 45 50

acter, the instrument being so constructed that one or more may be used, according to the position of an indicator or pointer, which is set at a point, so as to cause the instrument to render the desired signal, by the attendant before he leaves his instrument; but I have adopted as the most useful a set of time-signals, given by means of a disk having twelve notches, over which a contact-brush passes, and a mutilated plain disk or shield plate 55 connected to and moving with the pointer, so as to cover the twelve notches when the pointer is at zero or the "In" mark, thus providing a continuous surface for the contact-brush to pass over without making any breaks; or a few notches close together are uncovered when the insulated disk covers the whole of the twelve hour-indicating notches, so that a few quick impulses are sent over the line to the calling-station, indicating to the attendant that 60 some one is present at the called station. When the pointer is set opposite any one of the numbers on the dial of the instrument, a corresponding number of the notches are exposed, and the contact-brush makes the same number of breaks in passing over them, which number of breaks or induction impulses are sent over the line, and, actuating a suitable receiving-instrument, will notify the attendant at the calling-station of the time some one will be present 65 to receive the message or be put in communication with another subscriber. When the armature or moving part of the call apparatus or bell is in its normal position, and the automatic responding-instrument locked thereby, 70 its connecting-brush rests on an insulated plate, so as to break the circuit of the battery, whose current passes through said instrument when it is in operation. This battery, when the responding-instrument is applied to telephonic circuits, may be the one used with the telephonic transmitter, or be an independent 75 battery or other source of electrical energy.

It is evident that this automatic responding-instrument is well adapted to be used with 80 electrical systems other than telephonic, as will be clearly seen from its construction and operation, as set forth in the following description of the accompanying drawings, in which— 85 90 95 100

Figure 1 is an elevation of my automatic responding-instrument with the front of the case removed. Fig. 2 is a central vertical section on the line $\alpha\alpha$. Fig. 3 is a horizontal section on the line $\gamma\gamma$. Fig. 4 is a front view of the same on a smaller scale, showing the manner in which it is connected and applied to return signals over an electric circuit; and Fig. 5 shows its application to a telephonic circuit.

The working parts of the responding-instrument and the electro-magnetic device of the call apparatus are shown inclosed in the case a , the front of which is provided with a plate a' , marked with the word "In," and figures from 1 to 12 arranged in a semicircle. At the center of this semicircle projects the end of the shaft b , having secured thereto the index or pointer b' and knob b^2 , by which the pointer may be set opposite any of the marks or figures on the plate a' . Secured to the inner end of the shaft b is the shield-plate or mutilated disk c , between which and the front of the case a , securely fastened to the front of the case, is the metal disk d , having twelve equidistant teeth or notches, d' , formed in the upper half of its periphery, and a number of much finer teeth or notches, d'' , occupying a space equal to one of the teeth d' and adjacent to the first tooth of the series. A block of insulating material, e , is fixed in the lower central part of the disk d .

f represents a clock-movement or spring-motor, the last spindle, f' , of which is in line with the axis of the shaft b , and carries on its end, in close proximity to the shield-plate c , the wheel or disk g , provided with escapement-teeth on its periphery, which actuate the retarding escapement g' . This escapement g' has a tail-piece and adjustable weight, g'' , by the adjustment of which the speed of the wheel g may be regulated. This wheel g has secured to it the contact-brush h , which travels over the teeth d' and shield-plate c when the wheel revolves, but rests on the insulating-block e when the wheel g is in its normal position and at rest, in which position it is retained by the pin h' coming in contact with the arm i , secured to the shaft which carries the armature i' of the electro-magnetic device of the call apparatus. The call-bell i^2 is attached to the outside of the case, and is struck by the hammer i^3 , projecting from the armature i' , when the armature is attracted by the electro-magnet j , having its cores polarized by the permanent magnet j' .

l represents the spring of the motor, and l' the handle by which it is wound up.

The arrangement of this instrument in its simplest application is as follows, reference being also had to Fig. 4: The line-wire m joins one end of the wire on the magnet j ; the other end, m' , of the magnet-wire going to earth, and including in it the secondary coil m^2 of an inductorium, n . The primary coil n' of this inductorium is in circuit with the battery n^3 , and the automatic responding-instrument, which

is connected by the wire n^3 from the battery, being joined to the frame of the spring-motor f , so as to bring the contact-brush h in the circuit, and, by the wire n^4 , connecting the primary coil n' to the notched signal-disk d .

The operation is as follows: Upon a current being sent through the line-wire m to actuate the call apparatus, the magnet j attracts the armature i' , which draws the arm i away from the stop-pin h' , allowing the spring-motor to work, and thereby carrying the brush h around the disk d . The battery-current flows upon the brush h , leaving the insulated block e , and is broken each time the brush passes over the notches or teeth $d' d''$, which are exposed, thereby inducing corresponding electrical impulses in the coil m^2 , which are received and actuate any suitable receiving-instrument, as a telephonic receiver, m^3 , (shown in Fig. 5,) at the sending-end of the line. As soon as the call-current ceases, the spring i^4 moves the armature i' away from the magnet j in the position shown, and the wheel g is stopped after making one full revolution with the brush h resting on the insulated block e , thereby breaking the battery-circuit. Should this current induced in the coil m^2 actuate the armature i' , it will only cause the responding signal to be given by this call apparatus. Now, suppose the attendant of any given station has to leave his post and will return thereto at any hour, say six o'clock, he sets the pointer b' opposite the figure 6, which leaves six of the teeth d' exposed, as shown at Figs. 1, 2, 3, and 5, so that when this station is called, six distinct electrical impulses are automatically returned to the calling-station, indicating the time when said called station will be served. If the attendant be present, he sets the pointer to the "In" mark, as shown at Fig. 4. This causes the shield-plate c to cover the whole of the twelve teeth d' , but exposes the set of fine teeth d'' , the brush h , in passing over which, sends a few quick impulses over the line, indicating that some one is present. These teeth d'' are covered by the shield-plate c when one of the teeth d' is exposed, and remain covered during the exposure of any or all of the said teeth d' .

It is evident that until the spring of the motor is exhausted the instrument will repeat a signal as often as the releasing-magnet is actuated, and that instead of time-signals the disk d may be made to give any predetermined signal or set of signals, according to the requirements of the case and the class of electrical circuit the automatic responding instrument is applied to.

In the application of my automatic responding-instrument to telephonic circuits the connections may be made, as shown at Fig. 5, to cause the same to properly operate with the other instruments or devices used in the system; but said instrument will operate in the manner just described, as shown at Fig. 4, and the parts of the circuit at Fig. 5 corresponding thereto are similarly designated, so that

the functions performed thereby may be readily traced out and understood. The inductorium n and the battery n^2 , used in conjunction with the automatic responding-instrument, also form part of the telephonic transmission device, of which o represents a microphonic transmitter, connected by the wire o' to the wire n^3 , and by the wires $o^2 o^3$ and spring contact-switch o^4 to the coil n' , which completes the circuit of the microphone o , the primary coil n' of the inductorium, and the battery n^2 when the switch o^4 is closed. The line-wire m' has included in it the switch r , which is closed by one end of the lever s when the telephonic receiver t is suspended from a hook on its other end. This telephonic receiver t is joined to line-wire m through the wire t' , spring t^2 , which makes contact with the lever s when the telephone is removed therefrom, said telephone being connected to the lever s by the wire t^3 , and to earth through the wire m' by means of the wire t^4 . The spring t^2 is provided on its under side with the insulated block s' , which closes the spring-switch o^4 when the lever s is released. u represents a magneto-machine for calling up another station from this end of the line. It is out of circuit, except when the switch u' is moved onto the contact-point u^2 ; and v represents a magneto or other generator at the calling-station, by means of which the call apparatus $i j$ is operated; and m^3 is a telephonic receiving-instrument, by means of which messages and the automatic responding-signals are received at the calling-station.

The various parts occupying the positions shown in the drawings, a current or currents sent over line m from the generator v actuates the call apparatus $i j$, which allows the current from the battery n^2 to pass through the automatic responding-instrument and send a return-signal to the receiver m^3 in the manner before described, the telephone t and microphonic transmitter o now being out of circuit and inoperative. When a communication is to be sent from or received at this station, the receiver t is removed from the lever s , which, being actuated by the spring s' , cuts out the call apparatus $i j$, throws the receiver t into the circuit and the microphone o into the battery n^2 and primary coil n' into circuit. The responding-instrument is now also out of circuit by reason of its contact-brush h resting on the insulated block e , from which position it cannot be disturbed until the call apparatus is again in circuit and operated as before described.

Having now described my invention, what I claim, and desire to secure by Letters Patent, 60 is—

1. The combination, with an electro-magnet having a movable armature and call-bell operated thereby, an electric circuit, and means for operating the call-bell from a distant station, of a responding-instrument in a local circuit at the same station, the signaling mechanism of which is released free to act by the

armature of the call-bell when the call-bell is actuated, substantially as and for the purpose set forth. 70

2. The combination, with the secondary coil of an inductorium, an electric circuit, and a call apparatus, of an automatic return-signal instrument, a locking device in the return-signal instrument and actuated by the call apparatus, the primary coil of the inductorium, a battery, and a local circuit, substantially as and for the purpose set forth. 75

3. In combination, an inductorium, a battery, and an automatic responding-instrument 80 provided with a signaling device and connected motor included in a local circuit, a call or bell apparatus constructed, when at rest, to lock the signaling device of the responding-instrument, and means for operating the call-bell, and the secondary coil of the inductorium included in the line-circuit, substantially as and for the purpose set forth. 85

4. In a telephonic system, a microphonic transmitter, a switch, the primary coil of an inductorium, and a battery in an independent circuit, in combination with the signaling device or contact-spring and disk of an automatic responding-instrument, having a break-wheel located in a branch starting from a 90 point between the microphonic transmitter and the battery and between the switch and the primary coil of the inductorium, said branch being normally opened at the break-wheel, substantially as and for the purpose set forth. 95

5. In an automatic responding-instrument, in combination, a fixed disk or plate having a series of teeth or notches representing different signals and an insulated block on its periphery, a contact-brush carried by a rotating 105 shaft concentric with the disk, a motor for imparting motion to said brush, and a locking device for holding the brush stationary on the insulated block and actuated by an electric current to allow the brush to be rotated 110 by the motor, substantially as and for the purpose set forth.

6. In an automatic responding-instrument, in combination, a fixed disk or plate having a series of notches or teeth, a shield-plate arranged concentrically with the fixed disk and connected to and operated by an index-pointer, a dial-plate having marked thereon the signals the instrument is adapted to give, and a contact-brush carried by a wheel or disk whose 115 axis is coincident with that of the shield-plate and fixed disk, and motor for causing the contact-brush to travel around the fixed disk or plate, substantially as and for the purpose set forth. 120

7. In combination, a battery, the primary coil of an inductorium, the signaling device of an automatic responding-instrument constructed to be operated by means of a motor to indicate by inductive action in the line-circuit any of a set of predetermined impulses, 130 a receiving-instrument, a call apparatus constructed to lock the automatic responding-instrument, the secondary coil of the inducto-

rium, and a current-generator included in the line-circuit, substantially as and for the purpose set forth.

8. In combination, the responding-instrument constructed and operated substantially as described, the battery n^2 , the primary coil n' of the inductorium n , the line-wire m , the call apparatus $i j$, adapted to lock the responding-instrument, the line-wire m' , the secondary coil m^2 of the inductorium n , and the receiving-instrument m^3 , and electrical generator, substantially as and for the purpose set forth.

9. In combination, the automatic responding-instrument composed of the disk d , insulated block e , contact-brush h , carried by and forming a part of the motor f , the battery n^2 , the connecting-circuit $n^3 n^4$, and the primary coil n' of the inductorium of a telephonic transmitter, substantially as and for the purpose set forth.

10. A telephonic system comprising the following instrumentalities: the call apparatus $i j$, spring-switches $r t^2$, lever s , receiver t , and the secondary coil m^2 of the inductorium n included in the line-circuit, the microphonic transmitter o , battery n^2 , automatic responding-instrument $d e h f$, the switch o^4 , and primary coil n' of the inductorium included in a local circuit, in combination, substantially as set forth.

11. In an automatic responding-instrument for electric circuits, in combination, the spring-motor f , the contact-brush h , the fixed disk d , provided with the teeth d' , the insulated block e , the circuit-wire n^3 , connected to the motor

f , and the wire n^4 , connected to the disk d , the primary coil n' of the inductorium, and the battery n^2 , substantially as set forth.

12. In an automatic responding-instrument for electric circuits, in combination, the fixed disk d , provided with the teeth d' , the shield-plate e , shaft b , pointer b' , the dial-plate a' , and the rotating contact-brush h , carried by the disk g , whose axis is coincident with that of the fixed disk d , and shield plate e , substantially as set forth.

13. In an automatic responding-instrument for electric circuits, in combination, the wheel g of a motor, the contact-brush h , the stop-pin h' , the arm i of the armature i' of an electromagnetic device, the adjustable shield-plate e , the fixed toothed disk d , and the insulating-block e , substantially as set forth.

14. In an automatic responding-instrument for electric circuits, in combination, the fixed disk d , provided with the series of teeth d' and the series of small teeth d^2 , the rotating brush h , the insulated block e , and the shield-plate e , adapted to cover all the teeth d' and leave the teeth d^2 exposed, and to expose one or more of the teeth d' and at the same time cover the teeth d^2 , substantially as and for the purpose set forth.

Signed at New York, N. Y., this 5th day of August, A. D. 1884.

ALFRED G. HOLCOMBE.
